UNITED STATES PATENT OFFICE.

EBER HUBBARD, OF ST. JOSEPH, MICHIGAN.

MACHINE FOR THE MANUFACTURE OF PAPER PAILS.

SPECIFICATION forming part of Letters Patent No. 244,607, dated July 19, 1881.

Application filed August 30, 1880. (No model.)

To all whom it may concern:

Be it known that I, EBER HUBBARD, of St. Joseph, Berrien county, Michigan, have invented an Improvement in Machines for Making Paper Pails, of which the following is a specification.

The nature of this invention relates to certain new and useful improvements in the construction of machines for the manufacture of paper pails; and the invention consists in the peculiar construction of the devices employed for forming the croze to receive the bottom, and is particularly designed as an improvement upon the invention for which Letters Patent of the United States were granted to me April 20, 1880, and numbered 226,752.

Figure 1 is a central vertical section. Fig. 2 is a top plan. Fig. 3 is a bottom plan. Fig. 4 is a plan view of one of the segmental plates detached.

In the accompanying drawings, which form a part of this specification, G represents the press or mold, consisting of a perforated sheet-metal cone provided with the top spider, f, which is centrally perforated to admit of the insertion of the rod D, the full construction of this portion of the invention being contained in the before-mentioned Letters Patent.

In the arms of the spider f, and in the under face thereof, is formed a recess, a, to receive the annular ring A, which is provided with a stud, b, which projects up between the arms of the spider, and by which the ring may be turned, as desired.

B represents segmental plates, the inner ends of which are slotted, as shown at n, and through which slots pass screws c into the spider. Near the outer edges of these plates there is formed a slot, d, which receives a downwardly-projecting stud, e, from the spider, and which serves as guides to the plates as they are advanced or retracted. A pin or screw, g, projects from the inner face of each segmental

plate into the eccentric slots h in the ring A, the whole being so arranged that as the ring 45 is turned in one direction the plates B will be projected a proper distance beyond the face of the cone G, forming an annular flange, which, when the pulp is being pressed to shape, will form a croze in the same for the reception of 50 the head. The plates being retracted, the pail may be readily withdrawn from the mold or cone.

I am aware that an inner perforated conical former made in vertical sections, each of which 55 is provided with a narrow transverse rib, and capable of being expanded and contracted within an outer perforated former, so as to produce a paper-pulp pail with a croze, has heretofore been employed; that an inner conical former has heretofore been employed with a detachable flaring former of less diameter placed thereon to form a shoulder at their junction, near the small end of the pail, to support its bottom; that shoulders have heretofore been 60 formed on paper-pulp barrels and pails to support the heads of the former and the bottom of the latter; and that a projectible and retractile flange moving independently of a former has heretofore been used for forming a 65 croze in a pail; and therefore I lay no claim to either of these constructions, my invention being limited to the construction and combination of parts, as hereinafter claimed.

What I claim as my invention is—

The combination, with the former G and spider f, provided with the recess a, of the ring A, having the eccentric slots h, slotted segmental plates B, pins d, and screws c g, substantially as described, and for the purpose 80 set forth.

EBER HUBBARD.
